Attorney

UNITED STATES PATENT OFFICE.

PERCY S. BOLLES, OF FORT WORTH, TEXAS.

CHECK-BOOK.

1,198,183.

Specification of Letters Patent. Patented Sept. 12, 1916.

Application filed November 5, 1915. Serial No. 59,708.

To all whom it may concern:

Be it known that I, PERCY S. BOLLES, a citizen of the United States, residing at Fort Worth, in the county of Tarrant and State of Texas, have invented certain new and useful Improvements in Check-Books, of which the following is a specification.

My invention relates to check pads or books and more particularly to pads which 10 may be carried in the pocket without folding the blank checks; and the object is to provide check books or pads which can be carried in the pocket or other close place without folding the blank checks and to provide 15 pads of blanks with backs for the protection of the blank checks. Other objects and advantages will be more fully explained in the following description and the invention will be more particularly pointed out in the 20 claims.

Reference is had to the accompanying drawings which form a part of this application.

Figure 1 is a perspective view of a pad of 25 blank checks with the cover closed thereon. Fig. 2 is a perspective view of the same with the cover and stubs opened for writing a check. Fig. 3 is a perspective view with the cover opened and the stub blanks folded 30 down on the check blanks for making an entry on the stub.

Similar characters of reference are used to indicate the same parts throughout the several views.

35 The blanks are arranged in pads which are provided with a back 1 and a foldable cover 2. The blanks 3 are arranged to lie flat with the back 1 as a support and protector and not to be folded. The cover 3 is 40 connected to the back 1 by a foldable or flexible connection 7 which may be bent or folded as often as desirable without breaking. The blanks 3 are provided with record blanks 4. The record blanks 4 may be 45 continuations of the paper which forms the blanks, but the particular record blank on which the memorandum is being made will not be of the same piece of paper as the check to be written unless it should be that 50 the middle blank and the middle record blank would be reached at the same time.

The record blanks are provided with conventional indications which are on the reverse side from the indications on the blank checks. Lines of perforations 5 are provided so that the check members can be detached from the record blanks. The perforations 5 are made adjacent to the foldable part of the back so that the stubs can fold on the blank checks, as shown in Fig. 3. 55 The record blanks 4 are attached to the part 2 of the back at the points in close proximity to the line of perforations 5 by means of staples 6, but it is apparent that the record blanks may be stitched to the cover 2. 60 The folding is in the line of perforations and record blanks are attached close to the line of perforations so that the outer ends of the record blanks are free and can be turned back against the cover 2 for filling 65 and detaching the checks. The record blanks and the front cover and the back cover hold the check blanks in flat position so that in writing a check the surface will be flat and not creased by folding. The 70 whole makes a pad in compact form which is short enough to carry in the pocket and the pad can be made with practically no more cost than the ordinary block of blank 75 checks. 80

What I claim, is,—

1. A check book or pad comprising a front cover and a back cover provided with a flexible connection, a plurality of sheets permanently attached to said front cover in close 85 proximity to said connection and perforated transversely along the line of said connection, each sheet forming a blank for a record and a blank for a check, the portions of said sheets to the right of said perforations forming blanks for checks having indications printed on the faces thereof and the portions of said sheets to the left of 90 said perforations forming record blanks having indications printed on the faces 95 thereof but on the reverse sides of the sheets from the indications on said check blanks.

2. A check book or pad having a front cover and a back cover provided with a flexible connection, a plurality of sheets lying 100 on said back cover and extending partly on said front cover, each sheet forming a blank

for a record and a blank for a check, staples attaching said sheets to said front cover in close proximity to said connection, said sheets being perforated transversely thereof 5 and along a line over the central part of said connection, the parts of said sheets to the right of said perforations forming blanks

for drawing checks and the parts of said sheets to the left of said perforations forming blanks for records.

10

In testimony whereof I set my hand this 30th day of April, 1915.

PERCY S. BOLLES.
